APPARATUS FOR SATURATING ROOFING FELT

Clarence Elbert Wilkinson, Port Neches, Tex., assignor, by mesne assignments, to The Texas Company, New York, N. Y., a corporation of Delaware

Application July 24, 1941, Serial No. 403,842

5 Claims. (Cl. 91—18)

This invention relates to the manufacture of prepared roofing material such as that made by the impregnation or saturation of felt or paper (hereinafter referred to as felt only) with asphalt or other bituminous compounds of a similar nature.

It is well known to be important in connection with the manufacture of prepared roofing that the largest possible number of voids in the felt be filled with the saturating compound. The presence of air and moisture in the felt interferes to a considerable extent with the impregnation or saturation thereof with the saturating compound, and if not eliminated, results in excessive foaming when the felt is immersed in the saturant in a saturating tank. It is therefore important that the contained air and moisture be expelled as completely as possible either before or during the impregnating or saturating process.

It has heretofore been discovered by others that there is an advantage in applying the hot liquid saturating material to one side only of the sheet of roofing felt, whereby any air or moisture contained within the voids in the felt is expelled through the opposite surface of the sheet. For example, the Miller Patent No. 1,636,750, patented July 26, 1927, discloses a process wherein the felt passes around a heated drum or drums and as the felt approaches each of the drums, saturating material such as liquid asphalt is applied to one face of the sheet. The spouts used for applying the saturating material are located adjacent to the drums so that the drums help to spread or distribute the saturating material laterally over the sheet as the spouts pour or flood it on the sheet. After the asphalt has been applied to one face of the felt adjacent to the drum, the felt passes under the drum, thereby effecting a spreading or distributing action upon the asphalt. The felt then travels a sufficient distance through the air to allow the asphalt or other saturant to thoroughly penetrate the sheet and to drive out the moisture and air from the other face of the sheet. The felt may be subjected to similar treatment by passing it around any desired number of heated drums and applying the hot asphalt or other saturant between the face of the felt and the surface of the drum.

I have found that improved saturation of roofing felt can be obtained by applying the hot asphalt or other saturant, not between the face of the felt and the surface of the drum as disclosed in the Miller patent, but directly at the top of

each of the heated drums so that the saturant runs off of the drums in both directions to come in contact with one surface of the sheet of roofing felt, part of the saturant coming in contact with the sheet just prior to its passing under the drum, and the remainder being applied to the same face of the sheet as its passes from beneath the drum.

From the foregoing it will be apparent that one of the objects of the present invention is to provide an improved apparatus for applying a hot liquid saturant such as asphalt to one surface only of a felt sheet being used in the manufacture of roofing shingles in order to saturate the sheet and force through the opposite face of the sheet any air or moisture contained in the voids thereof.

The drawing diagrammatically illustrates an apparatus embodying the present invention.

20 According to the present invention, a roll of roofing felt 10 to be saturated is arranged at one end of the saturating machine. As the felt is drawn from the roll 10 it passes over a guide roll 12 and is then threaded between a pair of upper and lower squeeze rolls 14, 14, one of which may be driven from a suitable source (not shown). After emerging from between the squeeze rolls 14, 14, the sheet passes upwardly over a looper roll 16 which may or may not be heated, and 25 then downwardly until it is threaded between a second pair of squeeze rolls 18, 18, similar to rolls 14, 14. Any desired number of pairs of squeeze rolls may be employed and any or all of them may be heated if desired.

30 A spout 20, or preferably a plurality of spouts, is positioned directly above the upper roll of each pair of squeeze rolls, and through this spout 20 hot asphalt or other liquid saturant is applied to the top surface of the upper roll so that it runs 35 downwardly in both directions, some to come in contact with one surface of the felt before it passes between the squeeze rolls, and the rest, which passes down the opposite side of the roll, coming in contact with the same face of the sheet after it emerges from between the squeeze rolls. The sheet receives a slight squeezing action in conjunction with the application of the hot saturant, and this squeezing action tends to 40 accelerate the penetration of the asphalt into the sheet. The action of the rolls tends not only to assist in spreading the saturant across the entire face of the sheet, but also to accelerate the penetration of the voids in the sheet and to more rapidly and completely expel air and moisture 45 from the opposite face. The second application

50 of the rolls tends to assist in spreading the saturant across the entire face of the sheet, but also to accelerate the penetration of the voids in the sheet and to more rapidly and completely expel air and moisture 55 from the opposite face. The second application

of the hot saturant to the same face of the sheet as it emerges from between the squeeze rolls enables the sheet to absorb still more of the saturant as it travels upwardly to and over the looper roll 16, and in this manner more uniform and thorough saturation of the entire sheet is obtained than in any method heretofore used.

As indicated above, upon emerging from between each of the pairs of squeeze rolls and having the hot saturant applied to one surface thereof, the sheet of felt passes upwardly and over one of the looper rolls 16, 16 which allows time for a certain amount of cooling and permits the saturant to penetrate well within the voids of the sheet. Finally, after emerging from between the last pair of squeeze rolls and passing about a looper as heretofore described, the sheet is passed through a saturating tank 22 where both faces of the sheet are further coated with hot asphalt or other saturant, and upon emerging from the saturating tank, the sheet is passed over one or more loopers 24 until it is in such condition that it can be wound up into a roll, as shown at 26.

As hereinbefore indicated, the several squeeze rolls as well as the looper rolls may be heated as desired. The distance between the squeeze rolls and the looper rolls may be adjusted to allow for sufficient cooling of the asphalt between each application of hot saturant to the sheet. In this connection it might be said that the temperature of the saturant should preferably be approximately 425° F. or at least within the range of 400-450° F. for most efficient operation.

Obviously, many modifications and variations of the invention as herein described may be made without departing from the spirit and scope thereof, and therefore only such limitations should be imposed as are indicated in the appended claims.

I claim:

1. Apparatus for saturating a felt sheet comprising cooperating upper and lower squeeze rolls between which the felt sheet is passed, means for rotating said rolls, a spout disposed directly above the center of the upper roll and directed to feed hot saturant to the top of said roll so that the saturant will flow down both sides thereof to contact one face of the sheet both as it enters between and emerges from said rolls, a looper roll disposed above the squeeze rolls and over which the sheet is passed to permit absorption of the saturant by the felt, and a saturating tank through which the sheet passes and in which both sides of the sheet are coated.

2. Apparatus for saturating a felt sheet com-

prising cooperating upper and lower squeeze rolls between which the felt sheet is passed, means for rotating said rolls, a spout disposed above the upper roll and directed to feed hot saturant to the top of said roll so that the saturant will flow down both sides thereof to contact one face of the sheet both as it enters between and emerges from said rolls, and means for suspending the moving sheet in the air for a distance sufficient to permit absorption of the saturant from one face and the expulsion of air and moisture from the opposite face thereof.

3. Apparatus for saturating a felt sheet comprising cooperating upper and lower squeeze rolls between which the felt sheet is passed, means for rotating said rolls, a spout disposed above the upper roll and directed to feed hot saturant to the top of said roll so that the saturant will flow down both sides thereof to contact one face of the sheet both as it enters between and emerges from said rolls, means for suspending the moving sheet in the air for a distance sufficient to permit absorption of the saturant from one face and the expulsion of air and moisture from the opposite face thereof, and a saturating tank through which the sheet is passed and in which both sides of the sheet are coated.

4. Apparatus for saturating a felt sheet comprising cooperating upper and lower squeeze rolls between which the felt sheet is passed, means for rotating said rolls, a spout disposed above the upper roll and directed to feed hot saturant to the top of said roll so that the saturant will flow down both sides thereof to contact one face of the sheet both as it enters between and emerges from said rolls, a looper roll disposed above the squeeze rolls and over which the sheet is passed to permit absorption of the saturant by the felt, and means for applying additional saturant to both faces of the sheet.

5. Apparatus for saturating a felt sheet comprising cooperating upper and lower squeeze rolls between which the felt sheet is passed, means for rotating said rolls, a spout disposed above the upper roll and directed to feed hot saturant to the top of said roll so that the saturant will flow down both sides thereof to contact one face of the sheet both as it enters between and emerges from said rolls, means for suspending the moving sheet in the air for a distance sufficient to permit absorption of the saturant from one face and the expulsion of air and moisture from the opposite face thereof, and means for applying additional saturant to both faces of the sheet.
